A. L. VISSAT

RAILWAY FROG

Filed March 26, 1927

UNITED STATES PATENT OFFICE.

ANTHONY L. VISSAT, OF JEANNETTE BOROUGH, PENNSYLVANIA.

RAILWAY FROG.

Application filed March 26, 1927. Serial No. 178,579.

More particularly my present invention relates to that type of railway frogs wherein the interruptions in the fixed rails are completed by means of rail portions carried by 5 a movable frog plate which is shifted in unison with the switch.

Among the objects which I have in view are the following:

10 The improvement of the design and construction of the frog to increase its strength, durability and efficiency in operation.

15 The provision of improved means whereby the bed plate of the frog structure may be spiked to the ties and embedded in the ballast and whereby the movable frog plate may be installed in place on the bed plate and dismounted therefrom without disturbing the bed plate or removing the ballast in which it is embedded.

20 The arrangement of the connections by which the movable frog plate is shifted whereby no portion of said connection is located under or extends beneath the bed plate or interferes with the permanency of the ballast.

25 The prevention of torsional or lateral movement of the rail portions of the movable frog plate under passing traffic.

30 The prevention of the movable frog plate from jumping or otherwise becoming accidentally disengaged from or displaced relative to the bed plate.

35 The provision of means for guiding the movable frog plate in its shifting movements, thus insuring proper and complete registration of its rail portions with the stationary rail portions.

40 The construction of the rail portions so that there is no jarring as the wheels pass over the rail joints or hammering of the ends of the rails or rail portions.

45 The provision of improved means for preventing the entrance of foreign material or water to the sliding connections between the bed plate and the movable frog plate.

Other novel features of construction, and 50 also of arrangement of parts, will appear from the following description.

The improved frog plate structure whose 55 principles are hereinafter described provides new and improved means for the accomplishment of the objects above set forth.

In the accompanying drawings, wherein I have illustrated the best embodiment of the principles of my present invention now 55 known to me, Fig. 1 is a plan view of the railway frog, the movable frog plate being positioned to complete the fixed rails of the tangent track, and the cover plates being omitted; Fig. 2 is a longitudinal section along 60 the line II—II in Fig. 1; Fig. 3 is a section along the line III—III in Fig. 1; Fig. 4 is a plan view of the bed plate with the associated parts removed; Fig. 5 is a plan view with the movable frog plate dismounted from the bed 65 plate and also showing the shifting connections and the cover plate; Fig. 6 is a sectional detail taken along the line VI—VI in Fig. 5, and Fig. 7 is an inverted perspective of one of the cover plates. Fig. 8 is a detail in section 70 on line VIII—VIII in Fig. 1.

Referring to the drawings the frog structure in general comprises four main elements, viz, the bed plate 1, the two end members 2 and 3 which are hereinafter referred to as 75 "end castings" and the movable frog plate 4 which is mounted on the bed plate 1 and is slidable transversely of the latter. The end members 2 and 3 and the movable frog plate 4 are preferably castings of hard steel, such 80 as manganese or other suitable alloy, while the bed plate 1 may be of rolled steel. This selection of materials facilitates the movements of the movable frog plate on the bed plate as the surfaces in sliding contact are 85 of different material.

The frog structure is supported on the usual rail supports such as the cross ties 5^a, 5^b, 5^c, 5^d, 5^e, 5^f and 5^g, the bed plate being directly supported by the cross ties 5^a, 5^b, 5^c, 90 5^d and 5^e to which it is secured by spikes 6 which are driven through the holes 6^a in the bed plate. The spike holes 6^a in the central portion of the bed plate 1 are arranged in transversely disposed rows for a purpose to be 95 hereinafter described.

One end of the bed plate 1, the left end thereof in Figs. 1 and 4, is provided with an extension 7 of narrower width than the body of the bed plate and having a squared outer 100 end. The end casting 2 is undercut adjacent to its inner end so as to overlap inwardly over the extension 7, and said casting is provided with a vertical shoulder 8 which abuts

against the squared end of said extension 7. The end casting 2 is secured to the extension 7 of the bed plate by means of bolts 9 which extend through vertically disposed holes in the two parts. The lower surface of the under portion of the end casting 2 is also provided with one or more, preferably two, squared lugs 10 which snugly fit into socket holes 11 in the extension 7, thus relieving the bolts 9 of undue strain and torque and also facilitating the proper assemblage of the end casting with the bed plate.

Likewise the other end of the supporting plate is provided with a similar but preferably shorter extension 7^a and the end casting 3 is undercut to overlap said extension 7^a and is secured to said extension by the bolts 12 and also by means of its bottom lug 13 fitting snugly into the socket hole 14 of the extension 7^a. The under side of the end casting 3 is provided with a vertical shoulder 15 which fits against the squared outer end of the extension 7^a.

The end casting 2 is spiked to the ties 5^e and 5^f, while the end casting 3 is spiked to the tie 5^e. The heads of the bolts 9 and 12 are spaced between the ties.

16 and 17 represent the parallel rails of the tangent track, while 18 and 19 represent the parallel rails of the intersecting track, the rails 17 and 18 being gapped or interrupted to allow for the frog structure.

Formed integrally on the end casting 2 are the two rail members 20 and 21 which are aligned with the adjacent ends of the track rails 17 and 18 respectively and are in angular relation with each other, preferably merging in a V with a squared apex. The rail members 20 and 21 stop short of the outer end of the end casting 2 and the sides of the casting are contoured so that the inner sides of the rail ends 17 and 18 will fit snugly up against the casting with their extremities abutting against and registering with the extremities of the rail members 20 and 21. The outer side surfaces of the rail members 20 and 21 are contoured similarly to the sides of a track rail, so that the standard angle bars 22 may overlap the rail joints on the outside and the bolts 22^a, extending through the angle bars and transversely through the casting may be employed to hold the angles and the rails rigidly in position, thus securing the rails 18 and 17 in fixed alignment with the rail members 20 and 21 of the end casting 2. Similarly the casting 3 is integrally provided with the rail members 23 and 24 which are aligned respectively with the adjacent extremities of the track rails 17 and 18. The inner ends of the rail members 23 and 24 are also aligned respectively with the rail members 20 and 21, but the rail members 23 and 24 preferably do not merge with each other at their inner ends, to allow clearance for the travel of the flanged wheels along the rail member

23. The outer ends of the rail members 23 and 24 stop short of the outer end of the casting 3 and the end portions of the rails 17 and 18 fit snugly against the sides of the casting 3 and abut against and register with the extremities of the rail portions 23 and 24, angle bars 25 overlapping the joints on the outside and being secured in place by the bolts 26 extending through the casting 3.

The movable frog plate 4 is provided with two rail members 27 and 28 in angular relation to each other and so disposed that when the frog plate is shifted into the position shown in Fig. 1, the rail member 27 fills the gap between the adjacent end of the rail members 20 and 23 and thus completes the track rail 17, and when the movable frog plate 4 is shifted into its other position, the rail member 28 fills the gap between the rail members 21 and 24 and thus completes the track rail 17.

The bed plate is provided with a pair of parallel and transversely disposed slotted openings 29 located closely adjacent to the inner ends of the extensions 7 and 7^a. 30 represent lugs integral with the movable frog plate 4 and depending from the bottom surface of the same and slidably fitting the slotted openings 29. Thus the lugs 30 guide the movable frog plate in its sliding movements relative to the bed plate 1 while preventing movements of the said frog plate longitudinally of said bed plate. The slots are of proper length so that when the movable frog plate is in the position shown in Fig. 1, to complete the track rail 17 the lugs 30 abut against the ends of the slots 29 which are uppermost in Fig. 4, and when the movable frog plate is shifted into its other position to complete the track rail 18 the lugs 30 bear against the ends of the slotted openings 29 which are lowermost in Fig. 4. It is thus evident that the slotted openings and the lugs, being adjacent to the ends of the movable frog plate, prevent the torsional or twisting movement of the frog plate under moving traffic which might impair the proper registration of the rail portions. The lugs 30 do not protrude below the under surface of the bed plate so that the shifting of the movable frog plate 4 does not interfere with the ballast nor is it interfered with by the latter. The vertical corners of the lugs 30 are rounded or beveled to facilitate the sliding of the lugs in the slotted opening and to strengthen the lugs.

The movable frog plate is held in flat sliding contact with the bed plate, thus preventing the movable frog plate from jumping upwardly under moving traffic. Thus I bevel downwardly the ends of the movable frog plate, as at 31, and undercut the inner ends of the end castings 2 and 3, as at 32, to fit with said beveled portions of the movable frog plate. Thus while the movable frog plate is free to slide transversely of the bed plate it is held down in flat contact with the bed plate.

The under surface of the movable frog plate 4 is recessed transversely as at 33 to provide clearance for the heads of the spikes 6 which have been driven through the spike holes 6^a into the ties. The mounting of the movable frog plate is thus prevented from interfering with the convenient attachment of the bed plate to the ties, and the width of said bed plate may be materially less than would be required were its spike holes placed outside of the path of movement of the movable frog plate. The recessing of the under surface of the movable frog plate also reduces the areas of the movable frog plate and the bed plate which are in sliding contact and thus aids in minimizing the friction.

At either side of the movable frog plate 4 and opposite the lugs 30, the said plate is provided with an outwardly extending pierced ear 34 and to the ears 34 on one side of the said movable frog plate 4 are pivotally secured, as by the bolts 35, the forked ends of the connecting rods 36 by means of which the frog plate is operatively connected to the switch-operating mechanism so that the frog plate will be moved properly in unison with the movable switch-rail. The bottom surfaces of the forked ends of the rods 36 do not extend below the bottom of the frog plate so as not to interfere with the movements of the latter relative to the bed plate nor to drag on the bed plate. The top surfaces of said forks do not extend above the top surface of the frog plate, so as to clear the wheel flanges. The movable frog plate is provided with ears 34 on either side so as to be adapted for either right or left hand connection as the switch may require.

To prevent the entrance of foreign matter, such as dirt or cinders, or of water into the slotted openings 29 or between the metal surfaces in sliding contact, I provide covering means, such as the cover plates 37 which may be of heavy gauge sheet metal or the like and which are held in place by the bolts 35 which connect the rods 36 to the ears 34. For this purpose of connection said cover plate is provided with the bolt holes 38 for the bolts 35. Said cover is also provided with a depending front flange 39 which extends downwardly between the forks and with depending end flanges 40 which close in the space between the outer side surfaces of the forks and ears.

At the other side of the movable frog plate, that not connected up with the operative rods 36, the cover plate is bolted to the ears 34.

The ends of the rail portions 20 and 21, 27 and 28, and 23 and 24, which are arranged for registration, are rounded off slightly, as shown in the drawings, thus preventing the hammering of the ends of the rail portions as the wheels pass over the same, thereby

reducing the jarring and also prolonging the life of the rail portions.

It is evident that the movable frog plate may be installed or removed for replacement without disturbing the bed plate from its position in the track and without disturbing the ballast. This greatly facilitates the installation and repair of the frog structure.

As there are no openings, recesses nor moving parts beneath the bed plate, there is no interference with operation on account of water or ice.

What I desire to claim is:—

1. A movable frog for railway tracks comprising a bed plate mounted at the rail crossing, an end member detachably connected to either end of said bed plate, said end members having rail portions aligned with the fixed track rails, and a movable frog plate slidably transversely of said bed plate and provided with rail portions which are arranged by the movements of said frog plate to complete the gaps between the rail members of said end members, said end members and said frog plate having interengaging portions which maintain the frog plate in flat sliding contact with the bed plate.

2. A movable frog for railway tracks comprising a bed plate mounted at the rail crossing, an end member detachably connected to either end of said bed plate, said end members having rail portions aligned with the fixed track rails, and a movable frog plate slidably transversely of said bed plate and provided with rail portions which are arranged by the movements of said frog plate to complete the gaps between the rail members of said end members, said end members having portions overlapping the ends of said frog plate to maintain the latter in flat sliding contact with the bed plate.

3. A movable frog for railway tracks comprising a bed plate mounted at the rail crossing, an end member detachably connected to either end of said bed plate, said end members having rail portions aligned with the fixed track rails, and a movable frog plate slidably transversely of said bed plate and provided with rail portions which are arranged by the movements of said frog plate to complete the gaps between the rail members of said end members, the ends of said frog plate being downwardly beveled to fit in sliding contact with undercut portions of said end members whereby the frog plate is held in flat sliding contact with the bed plate.

4. A movable frog for railway tracks comprising a bed plate mounted at the rail crossing, said bed plate being provided with transversely disposed slotted openings, a movable frog plate having rail portions and mounted on said bed plate and provided with depending lugs having a sliding fit in said slots, an end member detachably connected to each end

- of said bed plate and provided with rail portions in registration with the fixed track rails, the rail portions of said frog plate being brought into registration with the rail portions of said end members by the movements of said frog plate, and interengaging portions of said end members and said frog plate whereby the latter is held in flat sliding contact with the bed plate.
- 10 5. A movable frog for railway tracks comprising a bed plate mounted at the rail crossing, said bed plate being provided with transversely disposed slotted openings, a movable frog plate having rail portions and mounted on said bed plate and provided with depending lugs having a sliding fit in said slots, an end member detachably connected to each end of said bed plate and provided with rail portions in registration with the fixed track rails, the rail portions of said frog plate being brought into registration with the rail portions of said end members by the movements of said frog plate, and interengaging portions of said end members and said frog plate whereby the latter is held in flat sliding contact with the bed plate, the sliding movements of said bed plate being limited by the contact of said lugs with the ends of said slotted openings.
- 30 6. A movable frog for railway tracks comprising a bed plate mounted at the rail crossing, said bed plate being provided with transversely disposed slotted openings, a movable frog plate having rail portions and mounted on said bed plate and provided with depending lugs having a sliding fit in said slots, an end member detachably connected to each end of said bed plate and provided with rail portions in registration with the fixed track rails, the rail portions of said frog plate being brought into registration with the rail portions of said end members by the movements of said frog plate, and interengaging portions of said end members and said frog plate whereby the latter is held in flat sliding contact with the bed plate, the sliding movements of said bed plate being limited by the contact of said lugs with the ends of said slotted openings, and said lugs being closely adjacent to the ends of said frog plate to prevent torsional movement of the latter.
7. A movable frog for railway tracks comprising a bed plate mounted at the rail crossing, said bed plate being provided with transversely disposed slotted openings, a movable frog plate having rail portions and mounted on said bed plate and provided with depending lugs having a sliding fit in said slots, an end member detachably connected to each end of said bed plate and provided with rail portions in registration with the fixed track rails, the rail portions of said frog plate being brought into registration with the rail portions of said end members by the movements of said frog plate, the lugs being so positioned

relative to the slotted openings in the frog plate that when a lug engages the end wall of one of the slotted openings one of the rail portions of the frog plate is in registration with the corresponding rail portions of the end members.

8. A movable frog for railway tracks comprising a bed plate mounted at the rail crossing, said bed plate being provided with transversely disposed slotted openings, a movable frog plate having rail portions and mounted on said bed plate and provided with depending lugs having a sliding fit in said slots, an end member detachably connected to each end of said bed plate and provided with rail portions in registration with the fixed track rails, the rail portions of said frog plate being brought into registration with the rail portions of said end members by the movements of said frog plate, the lugs being so positioned relative to the slotted openings in the frog plate that when a lug engages the end wall of one of the slotted openings one of the rail portions of the frog plate is in registration with the corresponding rail portions of the end members.

9. In a railway frog, the combination of a bed plate spiked to the cross ties, and a movable frog plate slidably mounted on said bed plate and having rail portions which are arranged to be brought into position to complete the fixed rails of the track by the movement of the frog plate, the under surface of the frog plate being recessed transversely to provide clearance for the heads of the spikes securing the bed plate to the ties.

10. In a railway frog, the combination of a bed plate fixedly secured to the cross-ties and provided with transversely slotted openings, a frog plate slidably mounted on said bed plate and having depending lugs which have a sliding fit with said slotted openings, connections between the frog plate with the switch operating mechanism for shifting the frog plate, and transversely disposed cover plates at the sides of the frog plate and moving in unison therewith for covering said slots and said connections.

11. In a movable frog for railway tracks, the combination of a bed plate mounted at the rail crossing, a pair of stationary end members having rail portions registering with the ends of the fixed track rails, and a movable frog plate slidably mounted on the bed plate and provided with rail portions which are arranged to be brought into registration with the rail portions of the end members, the ends of said rail portions being laterally beveled to prevent pounding.

12. In a railway frog, the combination with a bed plate, and a movable frog plate slidably mounted on said bed plate and provided with rail portions which are arranged to be brought into registration with the fixed rails by the movement of said plate, the ends

of the rail portions having the corners of their heads rounded off to prevent pounding.

13. In a railway frog, the combination with a bed plate, and a movable frog plate 5 slidably mounted on said bed plate and provided with rail portions which are arranged to be brought into registration with the fixed

rails by the movement of said plate, the ends of the rail portions and of the fixed rails having the corners of their heads rounded off to prevent pounding.

Signed at Pittsburgh, Pa., this 19th day of March, 1927.

ANTHONY L. VISSAT.
